CLAIM

The ornamental design for an electric ambient control unit for beds or the like, as shown and described.

DESCRIPTION

FIG. 1 is a front elevational view of an electric ambient control unit for beds or the like showing my new design;

FIG. 2 is a top plan view thereof;

FIG. 3 is a rear elevational view thereof;

FIG. 4 is a bottom plan view thereof;

FIG. 5 is a left side elevational view thereof, the right side being a mirror image of that shown;

FIG. 6 is a front elevational view of an electric ambient control unit for beds or the like, showing a second embodiment of my new design;

FIG. 7 is a top plan view of FIG. 6;

FIG. 8 is a rear elevational view of FIG. 6;

FIG. 9 is a bottom plan view of FIG. 6; and

FIG. 10 is a left side elevational view of FIG. 6, the right side being a mirror image of that shown.

FIG 1
